UNITED STATES PATENT OFFICE.

SHANKER ABAJI BHISEY, OF LONDON, ENGLAND, ASSIGNOR TO SIR RATAN TATA, OF LONDON, ENGLAND.

TYPE-CASTING MACHINE.

1,228,524.

Specification of Letters Patent.

Patented June 5, 1917.

Application filed May 26, 1913. Serial No. 770,000.

To all whom it may concern:

Be it known that I, SHANKER ABAJI BHISEY, of London, England, have invented certain new and useful Improvements in Type-Casting Machines, of which the following is a specification.

This invention relates to a new or improved type casting machine of the kind in which the type molds are set in the periphery of a wheel which maintains continuous contact with a casting spout. Hitherto in such machines the molds have been set radially and the types have been extruded from them by the movement of the matrices 10 radially outward through the molds. This method results in wearing of the mold parts. Moreover the wheel has to be of considerable diameter in order that the curvature of the end of the mold which forms the bottom 15 of the type may be negligible, and the pressure of the periphery of the mold upon the casting spout causes wear of the molds resulting in their gradual shortening; while there is further wear between the molds and 20 the stationary cover plate, causing a reduction in the body of the type.

The object of the present invention is to obviate these defects and the primary feature of the invention consists in providing 30 between the casting spout and the molds proper a mold member or mold members in which tangs or break pieces are in some cases cast integrally with the types. By this provision all the wear between the casting 35 spout and the mold is taken up by the mold member or members aforesaid which for convenience may be termed break or tang molds and consequently the lengths of the effective parts of the types are invariable. 40 A further important though not necessarily essential feature of the invention consists in forming the molds parallel with the axis of the wheel instead of radially relative to the said axis and other important features consist 45 of improved methods of extruding and collecting the types, and in the method of forming nicks in the type.

The invention further comprises certain features of construction and arrangement 50 which are hereinafter described and set forth in the claims.

In the accompanying drawings Figure 1 is a front elevational view of a machine constructed in accordance with my invention. 55 For convenience of illustration the nozzle

plate is removed and sections of the machine at different planes indicated at X—X and Y—Y of Fig. 2.

Fig. 2 is a sectional view on line A—A of Fig. 1 with the details of the molds omitted. 60

Fig. 3 shows the molds in detail to an enlarged scale the view being a section on line B—B of Fig. 1 with the central portions of the wheel omitted and one mold shown in the closed or casting position and the other in 65 the fully open position.

Fig. 4 illustrates a method by means of which the types can be transferred to the collecting chute.

Fig. 4^a is a side elevational view partly in 70 section illustrating an alternative manner in which the types are transferred from the casting machine to a collecting chute their tangs or break pieces being removed in the process, provided the types are cast with 75 break pieces.

Fig. 5 is a diagrammatic elevational view 80 of the mold wheel illustrating the possibility of casting and collecting types at two positions of the mold wheel.

Fig. 6 is a plan of Fig. 4.

Fig. 7 is a plan view illustrating a bifurcated platform by means of which the types 85 can be removed from a mold by a platform having a bifurcated end which projects beneath the character and the tang.

Fig. 8 is a section on line C—C of Fig. 7.

Fig. 9 is an enlarged view of a detail 90 shown in Fig. 1 designed to illustrate more clearly the manner in which the cast types are delivered to the receiving platform.

Fig. 10 is a plan view of Fig. 9 and Fig. 11 is a section on line Z—Z of Fig. 3.

Fig. 12 is a detail of a mold block.

Referring to these drawings and particularly to Figs. 1, 2 and 3 the numeral 1 designates the mold wheel which is suitably supported in bearings 2 carried by means of standards 3 and by any suitable mechanism this mold wheel 1 continuously rotates. The 100 body of the mold wheel 1 may be provided with water cooling recesses 4 the cooling water being introduced into these recesses through the pipe 5 and passing out through the passages 6 and final outlet 7. Around the periphery of the mold wheel 1 molds 8 parallel to the axis of the wheel are arranged. The molds are arranged in groups separated by the blocks 9 and each group of molds is made up of L-shaped blocks comprising body and 110

set width pieces 10 and wall pieces 10^a as clearly shown by Fig. 12. The molds are closed by cover plates 11 each group of molds having a common cover plate. The 5 inner ends of the molds are of course closed by the matrices 12 and the casting spout 13 fits in a V-shaped groove in a member 14 interposed between the molds and the casting spout. For convenience this member—the 10 provision of which is a primary feature of the present invention—may be termed the break forming member of the mold although as will hereafter appear the types are cast without breaks in the form of machine 15 shown particularly in Figs. 1, 2 and 3. The further details of construction will be more readily apparent if described in conjunction with the operation of the machine which is as follows:

20 As aforesaid the mold wheel 1 continuously rotates carrying with it the member 14 which maintains continuous abrading contact with the casting spout 13 through which molten metal is continuously ejected. As 25 each mold passes the casting spout the metal passes into the mold through the orifice 15. This casting position is shown clearly in the lower half of Fig. 3 and during the period of casting the matrices 12 carried by the matrix blocks 16 are held firmly in position owing to the coöperation of the roller 17 with the matrix controlling cam 18 which is carried by the stationary annular frame 19. The matrix blocks 16 are separated from the 30 roller carrying block 20 and a strong spring 21 is interposed so that the pressure from the cam 18 is transmitted through this spring and thus any backlash or irregularity due to wear or other causes is automatically 35 provided for. The matrix blocks 16 and their associated parts are slidably mounted in the member 22. During the casting period the cover plate 11 of the mold is also subjected to a final closing pressure by reason of its roller 23 being in engagement with the cover plate cam 24 and here again this 40 final closing pressure is transmitted through a spring 25.

50 The mold wheel is as has previously been explained continuously rotating and the abrading movement between the nipple of the casting spout 13 and the member 14 serves to wipe the metal away from the feet of the type so that the type are cast in this 55 instance without break pieces. The cast types are now in the mold and it is necessary that they be extruded and removed before the mold again reaches the casting position. When the cover plate roller 23 leaves the cam 24 the cover plate moves slightly 60 away from the type by means of springs 23^a and when the roller 17 passes the cam 18 the matrix blocks with their matrices 12 move away from the mold under the influence of the springs 26 shown clearly in Fig.

11 in a direction parallel to the axis of the wheel. The member 22 carrying the matrix block and matrices is controlled as to its radial position by the annular cam groove 27 cut in the stationary frame 19 through the 70 roller 28 mounted on a spindle 29 carried by the part 30 which is coupled by a pin 31 to the part 32 which is in turn connected to the member 22. The pin 31 passes through a slot 33 in the part 32 so that the parts 30 and 75 32 are relatively movable within limits and a spring 34 is interposed between the two parts 30 and 32 so that motion derived from the cam groove 27 is under certain conditions as will hereafter appear transmitted through 80 this spring 34. The curvature of the cam 27 is such that after the casting operation has been completed and the matrices have moved clear of the cast types the matrices are carried radially until the extruding fingers 85 35 are entirely clear of the mold body, the types still lying in the mold cavities and when this position has been reached the mold is by reason of the coöperation of the roller 36 with the mold cam groove 37 cut in the stationary 90 frame 19 carried to the extreme open position shown in the upper half of Fig. 3. The curvature of the cam path 27 now causes the matrix block carrier 22 and the matrices to move back slightly toward the casting 95 position so as to bring the extruding fingers 35 behind the types as shown in the upper half of Fig. 3 and the exact position is controlled by a stop or ledge 38 the spring 34 serving to compensate for any irregularity 100 of the cam movement. The mold cam path 37 now causes the mold to move back to the casting position and simultaneously the roller 39 upon the end of the receiving platform 40 coöperates with the platform controlling 105 cam plate 41 cut in the stationary frame 19 and causes the platform 40 to follow the mold. As the mold body moves back the types in the mold come into contact with the stationary extruding fingers 35 and the types are thus transferred to the platform 40 as 110 will be readily understood. The mold now moves to the casting position again, the platform cam 41 causes the platform 40 to move back with the types upon it out of the way 115 of the matrices, the cam path 27 returns the matrices into alinement with the molds, the cam 18 presses the matrices into the casting position and the cam 24 applies the final closing pressure to the mold cover plate 11 120 and the casting operation is repeated.

125 The correct alinement of the matrices relative to the mold 1 can be determined by the blocks 42 and spring 34 again serving to absorb any irregularity in the movement. The cast types resting upon the platform 40 are carried around until the stationary platform 43 is reached when they are transferred to this stationary platform. The manner in which the transfer is effected will 130

be readily understood upon reference to Figs. 9 and 10. It will be seen that the platform 40 has grooves at either side formed by the L-shaped blocks 44 and when the stationary platform 43 is reached the end 44^a passes beneath the types between the L-shaped blocks 44 and as the wheel continues its rotation the types are left upon the stationary platform.

10 After the types have been completely withdrawn from the molds the mold wheel still continues rotating and the types are carried around until they pass on to the top of the stationary tangential platform 43 Figs. 9 and 10 upon which they are deposited as the mold wheel continues its revolutions.

In Figs. 7 and 8 I have shown the arrangement of platform and type when the type are cast with breaks.

20 As the mold wheel continues to rotate the types 85 come into position over a bifurcated platform 86 shown in Figs. 7 and 8 and the types are left upon this platform one of the furcations of which engages the character, and the other the "breaks" of the types. The succeeding deposits upon this platform cause the types in position to be pushed along in the manner before described in relation to the platform 43.

30 The types deposited in the foregoing manner either upon the platform 43 or the platform 86 may be transferred to a magazine chute 87 and this transfer can be effected by providing the end of the platform with a pivoted part 88 as shown in Fig. 4 and providing means whereby this platform is moved about its hinge 89 from time to time to cause the types 90 upon it to be tipped into the chute 87. The method however

40 which I prefer to adopt is illustrated in Fig. 4^a. According to this arrangement each successive mold deposits its types upon the platform 43 or 86, the type from one mold pushing the type in front of it farther along. It

45 will be clear that there are periods when no types are being transferred and the types on the platform remain stationary during this period. This period is utilized to transfer some of the type from the platform, this operation being effected in the following manner: At the end of the platform a member 91 of polygonal cross-section is mounted and one of the faces of this member always forms a continuation of the platform. This

50 member 91 is rotatable upon the axle 92 which carries a fixed cam 93. This cam 93 operates against the ends of a number of spring catches 94, one for each surface of the member, and is so arranged that as any

60 surface of the member moves into position to form an extension of the platform the catch 94 associated with this surface rises up in front of the type as shown. During the period when no types are being deposited upon the platform the member 91 is

caused to turn so that the surface supporting the types is tilted and another surface moves into position forming an extension of the platform. Simultaneously the one of the catches 94 which was projected in front of the types is withdrawn and the types slide into the chute 87. The types pass down this chute and where the types are cast in a comb with a common break piece they are arrested by the division walls of the chute. The sliding member 95 is now caused, by the cam 96, to contact with the break piece or tang and this tang or break piece is thus forced off. The types relieved of their break pieces are now separate and pass down the partitioned chute 87. Of course where the types are cast without break pieces as in the machine shown in Figs. 1-3 the separate types pass direct to a magazine or platform.

Fig. 5 shows diagrammatically how types may be simultaneously cast at the two positions 97 and 98 of the mold wheel and the cast types transferred to platforms 99 and 100 running tangentially on either side of the wheel.

What I claim and desire to secure by Letters Patent is:

1. In type casting machines a continuously rotating mold wheel, type molds carried in the periphery of the mold wheel, a casting spout, an annular mold member interposed between the type molds and the casting spout, means for causing the cast types to be extruded from the mold cavities, a platform tangential to the mold wheel upon which the extruded types are deposited as the mold wheel rotates and an inclinable extremity to said platform and means for inclining said extremity to cause said types to be delivered substantially as specified.

2. In type casting machines a continuously rotating mold wheel, type molds carried in the periphery of the mold wheel, a casting spout, an annular mold member interposed between the type molds and the casting spout, means for causing the cast types to be extruded from the mold cavities, and a platform tangential to the mold wheel, upon which the extruded types are deposited as the mold wheel rotates, an extremity of polygonal cross-section for said platform so arranged that the faces of the extremity form the end of the platform and means for rotating the extremity and discharging the types substantially as specified.

3. In type casting machines a continuously rotating mold wheel, type molds carried in the periphery of the mold wheel, a casting spout, an annular mold member interposed between the type molds and the casting spout, means for causing the cast types to be extruded from the mold cavities, a platform tangential to the mold wheel

upon which the extruded types are deposited as the mold wheel rotates, an extremity of polygonal cross-section for said platform so arranged that the faces of said extremity 5 form the extremity of the platform, means for rotating said first mentioned extremity and discharging the types, a chute down which the types pass and means for detaching the break pieces from the types as said 10 types pass down the chute substantially as specified.

4. In type casting machines a continuously rotating wheel, type molds carried in the periphery of said mold wheel, a casting spout, 15 an annular mold member interposed between the casting spout and the type molds, means for opening the molds after the types have been cast, extruding fingers adapted to enter the mold cavities, means for positioning the 20 extruding fingers behind the types in the molds and means whereby the molds move relatively to the fingers and cause said fingers to extrude the types, a reciprocating platform upon which the types are extruded 25 and a stationary platform tangential to the mold wheel to which the types on the reciprocating platform are transferred substantially as specified.

5. In type casting machines, a continuously 30 rotating mold wheel, type molds carried by the mold wheel, a casting spout, a mold member interposed between the type molds and the casting spout, means for closing the molds and adjusting the matrices, 35 movable nick forming protrusions located within the molds during casting and means for causing said nick forming protrusions automatically to move out of the molds to permit the cast types to be extruded substantially as specified.

6. In type casting machines, a mold wheel, type molds arranged in groups carried in the periphery of the mold wheel, mold cover plates common to all the molds in a group,

a casting spout, an annular mold member 45 interposed between the casting spout and the type molds, a matrix carrier, and means for moving the molds, cover plates and matrix carrier into and out of the casting position as the mold wheel rotates substantially 50 as specified.

7. In type casting machines, a continuously rotating mold wheel, type molds carried in the periphery of said wheel, a casting spout for delivering type metal to said 55 molds, and an annular mold member interposed between the casting spout and the type molds in wiping engagement with the spout whereby the effective length of the type proper is not affected by wear. 60

8. In type casting machines, a continuously rotating mold wheel, type molds carried in the periphery of said wheel, a casting spout for delivering type metal to said 65 molds, and an annular mold member interposed between the casting spout and the type molds in wiping engagement with the spout whereby the effective length of the type proper is not affected by wear, said annular mold member being rotatable with said 70 wheel.

9. In type casting machines, a continuously rotating mold wheel, type molds parallel with the axis and carried in the periphery of the mold wheel, a casting spout 75 for delivering type metal to said molds, and an annular mold member interposed between the casting spout and the type molds in wiping engagement with the spout whereby the effective length of the type molds proper 80 is not affected by wear, said annular mold member being rotatable with said wheel.

In testimony whereof I affix my signature in presence of two witnesses.

SHANKER ABAJI BHISEY.
